UNITED STATES PATENT OFFICE.

MARIUS C. A. LATOUR, OF PARIS, FRANCE.

TELEPHONE.

1,421,015.

Specification of Letters Patent. Patented June 27, 1922.

Application filed April 18, 1916. Serial No. 92,033.

(GRANTED UNDER THE PROVISIONS OF THE ACT OF MARCH 3, 1921, 41 STAT. L., 1313.)

To all whom it may concern:

Be it known that I, MARIUS C. A. LATOUR, engineer, residing in Paris, France, 22 Rue Tocqueville, have invented new and useful 5 Improvements in Telephones, for which I have filed applications in France, as follows: December 28, 1914, patented June 6, 1918, No. 488,190; March 1, 1915, patented March 27, 1919, No. 20,803, and March 9, 10 1915, patented March 27, 1919, No. 20,804.

This invention relates to improvements in telephones and has for its object to protect the telephone system against losses of current.

15 With this end in view the entire stationary or fixed part of the magnetic circuit of the telephone system is made of a plurality of segments of sheet metal cut and assembled with an insulating metal between the single 20 segments so that the whole has the appearance of a foliated block without magnetic connections.

In the accompanying drawing:

Fig. 1 shows one of the segments for the 25 stationary part of the magnetic circuit.

Fig. 2 is a similar view with an inductance in series with a source of current.

Fig. 3 is a similar view with a transformer.

Fig. 4 shows the transformer as automatic- 30 ally operating.

Fig. 5 is a view similar to Fig. 1 with the inductance in shunt.

Fig. 6 is a top plan view of a diaphragm.

Fig. 7 shows a diaphragm provided with 35 slots.

Fig. 8 shows a modified form of dia- phragm constituted by threads of soft iron juxtaposed between two parallel-threads $x\ x'$ and $y\ y'$.

40 Fig. 9 illustrates the use of the magnetic auxiliary circuit.

Fig. 10 shows the shape of current coming from a receiving wireless station having a telephone according to the present inven- 45 tion.

Fig. 11 shows the arrangement of the ex- citer coil in fractions.

In the drawing, F represents one of the 50 segments of sheet metal forming the electro- magnet of the receiver, B is the telephone wire and P represents the diaphragm, while e is the source of current for the permanent excitation of the magnetic circuit.

The losses of line currents by the ap- 55 pearance of so called Foucault currents in

the diaphragm P is avoided in the following manner:

The Foucault currents are produced within the field created by the action of the poles of the magnets upon the inner face of 60 the diaphragm. Therefore, the diaphragm according to the present invention is provided with incisions along a direction parallel to an axis passing through both poles, as for instance shown in Figure 7, which 65 represents the telephone in plan view seen from the top of the diaphragm in this figure the incisions of the diaphragm and the projections of the foliated polar pieces being shown. The size of the incisions is 70 very small and moreover they are adapted to be closed by a special substance capable of magnetic attraction so as to prevent any current of air passing through such inci- 75 sions.

In the modified form of diaphragm shown in Fig. 8 the diaphragm is formed by a plurality of juxtaposed soft iron threads disposed between two parallel suspension threads $x\ x'$ and $y\ y'$. In such a telephone, 80 thanks to the permanent excitation by the continuous current of the magnetic circuit, the diaphragm may be acted upon by much stronger inductions than those usually employed, precautions however, must be taken 85 to prevent the diaphragm from sticking to the pole pieces.

This result can be obtained by letting a certain pressure act upon the diaphragm, a pressure which is higher than the atmos- 90 pheric pressure and which is capable of counterbalancing totally or least in part the magnetic attraction permanently exerted upon the same.

The telephone forming the object of the 95 present invention can be used everywhere where the ordinary telephones are used. It is sufficient to provide a source of continuous current which is capable of furnishing the necessary current for the excitation of the 100 coil B, which is provided for in Figure 2 by means of providing a branch coil in connection with the coil B. It will be understood that some provision must be made for preventing the line current from passing 105 through this branch coil and I accordingly connect the inductance l in series with the source of current e, which overcomes this difficulty.

According to the illustration in Fig. 3 110

the line current acts on the exciter current by means of a transformer t and as shown in Fig. 4 this transformer may be an automatically operating transformer $a-t$. It is possible to interpose a capacity in the circuit of the coil with a view of counter-balancing the self induction of the coil B for the line currents without thereby impeding the circulation of the continuous exciter current. Therefore, as shown in Fig. 5 in derivation with the capacity c an appropriate inductance l is arranged. The capacity will allow the line current to pass while the inductance will let the continuous exciter current pass.

If the invention is to be applied to wireless telephony the same need only be substituted for the telephones actually used in the detector current and in cases where a battery is used the same may be employed for the excitation of the telephone.

In wireless telephony the telephone according to the present invention, thanks to its construction without permanent magnet permits its use in the heterodyne system of wireless telegraphy for receiving direct without the employment of a detector. It is sufficient to substitute for this purpose in the telephone illustrated in Fig. 1 for the source of continuous current, a local generator of local waves.

What I claim is:

1. A telephone receiver having a coil carrying the telephonic current, an electromagnet excited by said coil, said electromagnet having a magnetic circuit comprising a fixed portion associated with said coil to provide a permanent field and a movable diaphragm, having slits extending in a direction from pole to pole of the fixed portion for eliminating eddy current losses.

2. A telephone receiver having a coil carrying the telephonic current, an electromagnet excited by said coil, said electromagnet having a magnetic circuit comprising a fixed portion of laminated soft iron associated with said coil to provide a permanent field, and a movable diaphragm having slits extending in a direction from pole to pole of the fixed portion for eliminating eddy current losses.

3. A telephone receiver having a coil carrying the telephonic current, an electromagnet excited by said coil, said electromagnet having a magnetic circuit comprising a fixed portion associated with said coil

to provide a permanent field and a movable diaphragm of juxtaposed iron wire extending in a direction from pole to pole of the fixed portion for the purpose of reducing eddy current losses.

4. A telephone receiver having a coil carrying the telephonic current, an electromagnet excited by said coil, said electromagnet having a magnetic circuit comprising a fixed portion associated with said coil to provide a permanent field and a movable diaphragm having slits extending in a direction from pole to pole of the fixed portion for eliminating eddy current losses, said slits being substantially closed to substantially prevent passage of air therethrough.

5. A telephone receiver having a coil carrying the telephonic current, an electromagnet excited by said coil, said electromagnet having a magnetic circuit comprising a fixed portion of laminated soft iron associated with said coil to provide a permanent field, and a movable diaphragm having slits extending in a direction from pole to pole of the fixed portion for eliminating eddy current losses, said slits being substantially closed to substantially prevent passage of air therethrough.

6. A telephone receiver having a coil carrying the telephonic current, an electromagnet excited by said coil, said electromagnet having a magnetic circuit comprising a fixed portion associated with said coil to provide a permanent field and a movable diaphragm, having slits extending in a direction from pole to pole of the fixed portion for eliminating eddy current losses, a portion of said magnetic circuit being excited to substantially the saturation point.

7. A telephone receiver having a coil carrying the telephonic current, an electromagnet excited by said coil, said electromagnet having a magnetic circuit comprising a fixed portion associated with said coil to provide a permanent field and a movable diaphragm having slits extending in a direction from pole to pole of the fixed portion for eliminating eddy current losses, and means for damping the diaphragm.

In testimony whereof I have signed my name to this specification in the presence of two witnesses.

MARIUS C. A. LATOUR.

Witnesses:

JOSEPH BETHENOOF,
CARLTON HURST.
